FOLLOWER FOR LOOSE-LEAF BINDERS

Charles H. Franz, Jr., Wauwatosa, Wis., assignor
to The Hein Company, Milwaukee, Wis., a cor-
poration of Wisconsin

Application April 29, 1944, Serial No. 533,324

8 Claims. (Cl. 129—4)

1

This invention relates to a follower for loose leaf binders.

The follower functions to prevent tearing of border sheets in ring binders from repeated opening and closing of the binder, and also to facilitate closing of the binder by tending to raise the sheets on the rings to a point where they can lie straight.

Most followers are constructed of stiff fiber board and have enlarged holes for the ring posts. Some have attached metal lips on their inner edges for determining their location in the binder and making it possible to close the binder without binding of the sheets and follower on the posts. Such lips as heretofore constructed add considerable to the expense of the follower and are not suitable for use with binders of plastic material.

The principal objects of the present invention are to provide a less costly follower and one which will function more readily and easily and be suitable for use with binders of any material.

The invention is carried out by providing a cylindrical tubular roller at the inner edge of the follower sheet to thereby support the sheet by a rolling contact on the base of the binder. The rollers may be secured in loop like extensions cut from the same sheet of the follower material to be integral with the follower and the roller may be made by providing a flat thin strip of fiber or metal of a width fitting within the loop and forming the strip into a closed tube encircling the outer portion of the loop.

An embodiment of the invention is illustrated in the accompanying drawing in which:

Figure 1 is a perspective view of a portion of a binder showing the follower in place;

Figure 2 is a plan view of the follower broken away in the middle;

Figure 3 is an edge elevation of the follower as shown in Figure 2;

Figure 4 is a section taken on line 4—4 of Figure 2 transversely through the follower sheet and roller; and

Figure 5 is a plan view similar to Figure 2 showing the use of a roller with a modified loop and with the roller partially sectioned.

The follower comprises a sheet 1 preferably of stiff fiber material of a length corresponding to the length of the paper sheets 2 in the binder 3 and having a width usually substantially less than that of the sheets 2.

The follower sheet 1 has a series of holes 4 near the inner edge thereof for receiving the fixture posts 5 of the ring binder 3. The holes

2

4, instead of being circular as in sheets 2, are preferably oblong with a width substantially greater than the thickness of the posts 5 and a length about twice that of the width. The length of the holes and spacing of the same will be standard as in the case of the punching of sheets 2 for most ring binders.

In order to raise the follower along the sides of the posts 5 during closing, a rectangular loop 6 of the same fiber material is cut from the same stock as sheet 1 at the inner edge of the latter. Preferably there are two such loops 6, one near each end of the sheet 1, but there may be more loops if desired.

15 The loops are spaced unequally from the respective ends of the sheet 1 so that a follower may be paired with a similar follower in the same binder by merely reversing one follower end for end to prevent the corresponding loops of the followers from interfering with one another.

The loops 6 are of rectangular construction and each of the loops has the opening 7 therethrough constituting a long slit running parallel with the inner edge of the follower.

25 A roller 8 is formed on each loop 6 by bending a flat strip of suitable material, such as fiber or polished metal, around the outer closure of the loop into a closed tubular shape. The roller 8 should be sufficiently thin to pass through opening 7 in loop 6 with ease and of sufficient diameter to be loose on the loop 6 to allow for ready turning of the roller thereon.

The loop 6 may not form an extension on the sheet, and may constitute merely a slit or opening 35 7' in the body of the sheet 1' parallel and near to the inner edge of the sheet as shown in Figure 5. The roller 8' is then formed to pass through the opening 7'.

The rollers roll upon that portion of the fixture plate of the binder 3 intermediate the posts 5 and upon closing of the binder they tend to raise the follower sheet 1 and the note book sheets 2 supported thereby upwardly along the sides of the posts to a point where the sheets will lie flat with the binder covers.

45 The curved nature of the rollers makes it possible for them to fit beneath the inner edges of sheets 2 without interfering with them, and the rollers tend to separate the edges of sheets 2 on one side of the binder from those on the other side when the binder is open.

In so far as the rollers 8 tend to keep the sheets 2 on the opposite sides of the open binder separated they prevent interference sometimes resulting when the inner edges of the sheets en-

gage one another at the time of attempted turning of the pages of the binder.

Where binder fixtures of plastic material are employed the relatively large surface areas of contact between the rollers 6 and the fixture plates of the binder and the rolling nature of the contact prevents any undue wear or injury to the plastic base, even when metal rollers are employed.

The simplicity of the structure and the ease of its manufacture enables the follower to be made by mass production methods with very little waste of material and at considerably less cost than former followers. This is so without sacrificing any of the functional advantages involved, and in fact with a structure having added advantages over former followers.

The invention may have various embodiments within the scope of the accompanying claims.

I claim:

1. A ring binder follower for assembly with a binder having a fixture plate supporting a plurality of binder posts to hold sheets of material in the binder, and comprising a stiff sheet having holes along its inner edge for receiving the posts of the binder, and freely rotating roller risers mounted along its inner edge to support the same by rolling contact upon the fixture plate of the binder.

2. A ring binder follower for assembly with a binder having a fixture plate supporting a plurality of binder posts to hold sheets of material in the binder, and comprising a stiff sheet having holes along its inner edge for receiving the posts of the binder, and freely rotating roller risers mounted along its inner edge to support the same by rolling contact upon the fixture plate of the binder, said rollers constituting cylindrical tubular members encircling projections on the inner edge of the sheet.

3. A ring binder follower for assembly with a binder having a fixture plate supporting a plurality of binder posts to hold sheets of material in the binder, and comprising a stiff sheet having holes along its inner edge for receiving the posts of the binder, and freely rotating roller risers mounted along its inner edge to support the same by rolling contact upon the fixture plate of the binder, said rollers constituting cylindrical tubular members encircling closed loop-like projections on the inner edge of the sheet.

4. A ring binder follower for assembly with a binder having a fixture plate supporting a plurality of binder posts to hold sheets of material in the binder, and comprising a stiff sheet having oblong transversely extending holes along its inner edge for receiving the posts of the binder, a plurality of integral extensions at the inner edge of the sheet having elements extending parallel to and spaced from said edges, and a freely rotating tubular roller encircling said element of

each extension for supporting the follower upon the fixture plate of the binder.

5. In a ring binder having a fixture plate supporting a plurality of binder posts to hold sheets of material in the binder, a pair of followers disposed between the binder and the sheets of material and each comprising a stiff sheet having oblong transversely extending holes along its inner edge for receiving the posts on one side of the binder, a plurality of integral extensions at the inner edge of the follower sheet having elements extending parallel to and spaced from said edge, and a freely rotating tubular roller encircling said element of each extension for supporting the follower upon the fixture plate of the binder, said extensions and rollers being spaced apart equally on said pair of followers and unequally spaced from the respective ends of each follower to prevent interference between the extensions and rollers on the one follower with those on the other follower employed in the same binder when said followers are reversed end for end relative to each other.

6. In a follower for loose leaf binders having a central fixture plate, a follower sheet of stiff material and freely rotating rollers disposed along the inner edge thereof to provide rolling contact support therefor upon the fixture plate of the binder.

7. In a follower for loose leaf binders having a central fixture plate, a follower sheet of stiff material and freely rotating rollers disposed along the inner edge thereof to provide rolling contact support therefor upon the fixture plate of the binder; said rollers constituting tubular cylindrical members each having a side passing through a slot in the body of the follower sheet.

8. In a follower for loose leaf binders, a follower sheet of stiff material having a plurality of aligned slots extending parallel to the inner edge of the sheet near the same and spaced longitudinally therealong, and a plurality of relatively thin cylindrical rollers for corresponding slots, each of said rollers having one side passing through the corresponding slot to roll freely on that portion of the sheet between the slot and the inner edge of the sheet.
